R. B. LEWELLEN,
GARBAGE CAN,
APPLICATION FILED OCT. 7, 1919.

1,352,521.

Patented Sept. 14, 1920.

UNITED STATES PATENT OFFICE.

ROSA B. LEWELLEN, OF HYLTON, TEXAS.

GARBAGE-CAN.

1,352,521.

Specification of Letters Patent. Patented Sept. 14, 1920.

Application filed October 7, 1919. Serial No. 329,013.

To all whom it may concern:

Be it known that I, ROSA B. LEWELLEN, a citizen of the United States, residing at Hylton, in the county of Nolan and State of Texas, have invented certain new and useful Improvements in Garbage-Cans, of which the following is a specification, reference being had therein to the accompanying drawing.

10 This invention relates to a garbage can and the like and has for its object the production of a simple and efficient means for containing garbage and facilitating the opening of the lid of the garbage can.

15 Another object of this invention is the production of a simple and efficient buffer means for preventing the sliding of the door or cover when the door or cover is closed.

With these and other objects in view this 20 invention consists of novel constructions, combinations and arrangements of parts as will be hereinafter fully described and claimed.

In the drawings:—

25 Fig. 1 is a rear elevation of the can.
Fig. 2 is a side elevation thereof.

Fig. 3 is a section taken on line 3—3 of Fig. 1.

30 Fig. 4 is a vertical section taken on line 4—4 of Fig. 3.

Fig. 5 is a section taken on line 5—5 of Fig. 2.

Fig. 6 is a section taken on line 6—6 of Fig. 2.

35 By referring to the drawings it will be seen that 1 designates the body of the can which tapers toward the bottom thereof and is provided with a rearwardly extending spout 2 at its lower end. This rearwardly 40 extending discharge pipe 2 is adapted to extend through the partition 3 or wall of the dwelling in which the can is placed. The can is preferably placed flat against the wall 3 and held in engagement therewith 45 by means of securing screws 4 which pass through the edge 6 of the can 1 and engage the wall or partition 3 for firmly holding the can in a set position.

One side of the can 1 is provided with a 50 dove-tailed vertically extending channel 6 struck from the metal constituting the body 1 thereby producing inclined sides 7. A door operating rod 8 is slidably mounted within the dove-tailed channel 6 and this 55 door operating rod 8 is preferably dove-tailed in cross sections and is provided with

inclined side faces 9 for bearing against the inclined face 7 of the channel 6.

A plurality of brackets 10 are secured to the body 1 of the can upon either side of the dove-tailed channel 6 near the bottom thereof and an operating treadle 11 is pivotally mounted upon a pin 12 carried upon the bracket 10. The treadle 11 is provided with an inwardly extending finger 13 which engages the lower end of the lid lifting bar 14. The upper end of the lid lifting rod 14 engages the under face of the lid 15 and as the treadle 11 is depressed, the lid lifting rod 14 will be moved vertically thereby 65 swinging the lid 15 to an open position. The lid 15 is hingedly secured to the body 1 by means of the suitable spring hinge 16 which spring hinge 16' is adapted to hold the lid or door 15 firmly in a closed position. 70

A buffer spring 16 is secured firmly to the side of the can 1 by means of the securing bolt 17 and this buffer spring 16 carries a rubber cap 18 which is adapted to firmly 80 engage the edge of the cover 15 and hold the cover or lid 15 in a closed position and also prevent the lid from slamming or raising an unpleasant noise when the lid is closed.

By considering Fig. 5 it will be seen that 85 a longitudinally extending slot 19 is formed in one side of the body 1 in which fits the bolt 17 whereby the buffer spring 16 may be firmly held in an adjusted position upon the body.

It of course should be understood that the 90 discharge spout 2 may be connected to a sewer or other means of disposal of the garbage or may be connected to a receptacle such as a barrel and the like.

What is claimed is:—

1. A garbage can of the class described comprising a body, said body provided with a substantially dove-tailed channel formed in one side thereof, a door operating rod 100 reciprocatably mounted within said channel and being substantially dove-tailed in cross sections, a lid carried by said body, the upper end of said lifting rod adapted to engage said lid for facilitating the raising of said lid to an open position, a treadle carried by said body projecting under said lifting rod for raising said lifting rod as the outer end of said treadle is depressed, and a buffer adapted to be engaged by said door. 105

2. A garbage can of the class described, comprising a body, said body provided with

an inwardly-extending channel formed in its side, a door-operating rod tightly fitting said channel, a door hinged upon said body and overhanging and covering the upper end of
5 said channel, said rod being adapted to engage the inner face of the door and raise the same when moved upwardly in said channel,

and means engaging the lower end of said rod and detached therefrom for manually operating said rod to slide the same in the 10 channel and thereby open the door.

In testimony whereof I hereunto affix my signature.

ROSA B. LEWELLEN.
